TARGET THROWING MECHANISM

Harold F. Mossberg, New Haven, Conn., assignor
to O. F. Mossberg & Sons, Inc., New Haven,
Conn., a corporation of Connecticut

Application February 20, 1940, Serial No. 319,853

17 Claims. (Cl. 124—8)

This invention relates to target throwing mechanisms, and more particularly to improvements in such mechanisms which are especially adapted to project frangible disc-like targets, such as are commonly termed clay pigeons, into the air to be used for target practice by a marksman.

In an application Serial #311,531, filed December 29, 1939, for a patent on an improvement in trap guns, a target throwing mechanism, or trap portion, is shown which is adapted to be detachably and pivotally secured upon a firearm portion and to cooperate therewith, and this application may be considered as a continuation in part thereof, the mechanism shown herein being an improvement over the target throwing mechanism, or trap portion, disclosed therein, and which is adapted to be detachably mounted in its entirety upon a gun barrel, or other supporting member.

Most of the target throwing mechanisms now in general use are bulky, expensive to manufacture, in many instances being complicated in structure, and inconvenient to carry and use. Many of these mechanisms are of such construction that they require the services of an individual other than the marksman to actuate them, thereby preventing their use when such an individual is not available.

One of the objects of this invention is to provide an improved target throwing mechanism whereby the marksman can conveniently actuate it to throw targets without such operation seriously interfering with his use of a firearm, thus obviating the services of a second person.

Another object of this invention is to provide a target throwing mechanism having conveniently actuated means in its structure whereby it is adapted to be readily and detachably mounted upon the barrel of the firearm, or upon a similarly shaped holder, such as a bar or rod, which are either adapted to be held in the hand of the user, mounted on a tripod, or stuck into the ground and be vertically adjusted to position it to the user.

Still another object of this invention is to provide a target throwing mechanism of the above, or analogous, nature wherein an improved form of clamping member is provided to detachably secure the mechanism to a cylindrical bar, such as a relatively thin walled shotgun barrel, and which, due to its structure, evenly distributes pressure over a relatively large area, whereby any possibility of the bar, or gun barrel, being distorted is avoided.

A further object of this invention is to provide

in a target throwing mechanism an improved rod clamping device of the above nature which is adapted to also form the supporting means for the operative target throwing parts of the mechanism.

A still further object is to provide an improved target throwing mechanism which will be relatively inexpensive to manufacture, simple in construction, compact, of pleasing appearance, and which is very convenient, efficient, and durable in use.

With these and other objects in view, which will appear as the description proceeds, there has been illustrated in the accompanying drawings one form in which the invention may be conveniently and advantageously embodied in practice.

In the drawings, wherein like reference numerals designate like parts throughout the several views:

20 Figure 1 is a side elevational view of an improved target throwing mechanism mounted on a gun barrel and embodying the features and principles of this invention;

Figure 2 is a top plan view of the same, parts 25 thereof being shown in another position by dotted lines;

Figure 3 is a bottom view of the same;

Figure 4 is a sectional view taken on line 4—4 of Figure 1;

30 Figure 5 is a sectional view taken on the line 5—5 of Figure 1;

Figure 6 is a sectional view taken on the line 6—6 of Figure 2;

Figure 7 is a sectional view taken on the line 35 7—7 of Figure 2;

Figure 8 is a general view of the mechanism mounted on various supports;

Figures 9 and 10 illustrate, by sectional views similar to Figures 4 and 6, a somewhat different 40 arrangement of clamp screws; and

Figure 11 illustrates a somewhat different form of leaf spring adapted to releasably hold a target in the frame.

In accordance with the objects of this invention, the target throwing mechanism shown in the drawings is adapted to throw frangible targets 45 of disc-like form, as indicated by dotted lines in Figures 1 and 7, and preferably of the form shown in a copending application Serial No. 319,857 filed February 20, 1940. Such targets are thrown out into the air to be fired at by a marksman and preferably fly through the air with their circular bases generally in a horizontal plane presenting their side wall as a target area to the marksman and, when hit, shatter

into a number of pieces to visually indicate, while they are in the air, such a result. In order that the marksman may personally, and without assistance of a second person, actuate this mechanism to throw such target into the air in an efficient manner, the mechanism is adapted to be securely clamped upon either the barrel 11 of the firearm being used, or a bar 12 adapted to be fastened either to a handle 13, or to one of a pair of telescoping vertical rods 14 adapted to be stuck into the ground, or which may be suitably supported on a tripod 15, as indicated in Figures 1 and 8, to position the mechanism adjacent and convenient to the user in any desired gun firing position.

The means, whereby the mechanism may be conveniently and readily secured to a bar 12 to be firmly supported thereby, or to a shotgun barrel 11 having the usual relatively thin walls, and in order not to possibly distort this barrel by clamping pressure, comprises an elongated clamp including an upper member 16 and a lower member 17. The members 16 and 17 are fastened together, when clamped about the cylindrical barrel 11, or bar 12, by bolts 18 and 19, bolts 21 and 22, and screws 23 and 24, which pass through suitable laterally projecting corresponding lugs 25, and 26 provided on the members 16 and 17 respectively. By substantially elongating the members 16 and 17, as shown, the clamping pressure is distributed over a considerable lengthwise area of the gun barrel 11, or bar 12, whereby the clamp will be firmly held thereto and no distortion of the gun barrel will be experienced. By forming the elongated clamp of upper and lower members 16 and 17 respectively, which may be entirely separate from each other, it is possible to apply the same at any position upon a gun barrel, or the like, without removing any upstanding sights, or like parts, previously positioned thereon. By disposing the joint between the upper 16 and lower 17 members of the clamp substantially on the level of the axis, or medial line, of the barrel 11, the upper member 16 and the heads of the bolts 18, 19, 21, 22 and of the screws 23, 24 will not appreciably extend above the upper surface of the barrel and interfere with the use of the usual sights or distract the user when sighting the gun.

The target throwing means of this mechanism is adapted to receive and releasably hold the disc-like targets 10 thereon, slidably positioned between, and in, opposing channels 27 and 28 formed along the side edges of a sheet metal frame 29. The channels 27 and 28 may be made by bending up and over the edges of the material of which the frame 29 is made, and extend parallel to each other rearwardly from the frame front end 31 a desired amount. Rearward of the terminating ends 32 and 33, of the channels 27 and 28 respectively, vertical flanges 34 and 35 are provided, the flange 35, with the frame 29, converges rearwardly toward the other flange 34 and to a flat extension 36 and acts as a rearward stop for the target 10. A light tensioned leaf spring 37 is fastened at its forward end, as by spot welding, brazing, or soldering, to the forward end of the frame on the outer surface of the side wall of the channel 27, and extends rearwardly along this surface to a hole 38 formed in the wall of said channel 27. The spring 37 is bent inwardly at the hole 38, and has its end 39 extended through the hole 38 and transversely over the upper surface of the frame 29 a short amount, to lie in the path of the base rim of the target

10 to releasably hold the target in the frame 27 against the stop flange 35. The arrangement of the spring 37 and the cooperation of its end 39 with the rim of the target 10 is such that the end 39 will be pushed outwardly by the rim of the target 10 to release the same when the frame 29 is rapidly swung to throw the target forwardly therefrom.

The flat frame extension 36 is provided with a hole 41 to receive a journal boss 42 formed on a washer 43 whereby the frame 29 is pivoted about a screw 44 which secures the washer 43 to a bracket 45. The bracket 45 extends transversely across and beneath the lower clamp member 17 to be secured thereto by the screws 23 and 24 which extend downwardly from the member 17 through spacing collars 46 and 47 respectively, and screw thread into opposite ends of the bracket 45. When tightly screw-threaded into the ends of the bracket 45, the screws 23 and 24 act as common means to secure the bracket 45 to the lower clamp member 17 and to clamp the barrel 11, or bar 12, between the members 16 and 17.

25 A tongue 48 extends rearwardly from the flat frame extension 36 and is pivoted to the forward end of an elongated screw-threaded rod 49 by a pin 50. The screw-threaded portion of the rod 49 is screw-threaded into a thumb nut 51 which has a tapered, or like, extension 52 thereon about which the forward end of a relatively heavy tensioned coiled spring 53 is tightly wound to fasten it thereto, and to permit rotation of the nut 51 relatively thereto. The spring 53 extends rearwardly from the nut 51 and has its other end secured to the rear end of the clamp member 17 by hooking the last coil 54 of the spring 53 under a lug 55 struck downwardly from the material of the member 17 at its rear end. Swinging of the frame 29 rearwardly into the position indicated in dotted lines in Figure 2 greatly increases the tension of the spring 53 by stretching it and, therefore, when the frame 29 is released from such position, considerable centrifugal force is exerted to throw a target 10 from the frame. It is obvious that the spring tension can be varied by manipulation of the thumb nut 51.

Means is herein shown to releasably hold the frame 29 in its target throwing position, as indicated in dotted lines in Figure 2, and this means comprises a catch member 56 formed from the material of the frame 29 at the upper edge of the flange 34, or secured thereto, as by welding, brazing, soldering, or the like. The catch member 56 is disposed on the frame 29 in position to be engaged, in a notch 57 formed therein, by a sear-like depending end 58 of an elongated trigger member 59. The trigger member 59 is secured to and slidably supported on the lower clamp member 17 by the bolts 21 and 22 which pass downwardly through the corresponding lugs 25 and 26, respectively formed on the members 16 and 17, then through spacing collars 61 and 62 and screw thread into nuts 63 and 64 respectively. The collars 61 and 62 each have a cylindrical journal portion 65 (see Fig. 4) which lies in and passes through a longitudinally elongated hole 66 formed in the trigger member 59 at each bolt 21 and 22, see Figure 4. The bolts 21 and 22, therefore, act as common means to slidably secure the trigger member 59 to the lower clamp 17 and, through the collars 61 and 62, to clamp a barrel 11, or bar 12, between the clamp members 16 and 17. The bolts 18 pass through corresponding lugs 25 and 26 and screw

thread into nuts 67 and 68 respectively, to assist the bolts 21 and 22 in clamping a barrel 11, or bar 12, between the members 16 and 17. A coiled spring 69 is provided to maintain the sear-like end 58 of the trigger member 59 in position to engage the catch 56. The spring 69 is shown herein secured at one end to the bolt 22 and at its other end to the trigger member 59 through a hole 71 provided therein for this purpose. By pulling upon a finger piece 72, formed on the rear end of the trigger member 59, the catch 56 is released and the frame 29 will swing forwardly under the urge of the spring 53. By using the lower clamp member 17 as the common support for the frame pivot 44, the spring 53, and the trigger member 59, these parts may be disposed closely to the undersurface of the barrel 11 to form a compact assembly, which can be conveniently inserted into a gun case. Being so disposed in underslung relation to the barrel 11, the target throwing mechanism will not interfere with the use of the gun, should it be left assembled thereto, for other than target practice.

In Figures 9 and 10, the bolts 81, 81, and 82, 82, and screws 83 and 84, corresponding to the bolts 18, 19 and 21, 22 and the screws 23, 24 respectively, pass upwardly through the several parts instead of downwardly, as shown in Figures 1-6 inclusively. In this arrangement, the bolts 81 pass upwardly through the lugs 26 and 25 and have their cooperating nuts 85 on top of the lugs 25. The bolts 82 pass upwardly through the collars 61 and 62 and screw thread into the lugs 26, to secure the trigger member 59 to the clamp member 17 and then pass through the lugs 25 and are secured thereto by nuts 86 to clamp the members 16 and 17 onto the barrel 11, or bar 12. The screws 83, 84 pass upwardly through the ends of the bracket 45 and the collars 46, 47 and screw thread into the lugs 26, and then pass through the lugs 25 and are secured thereto by nuts 87 to clamp the clamp members 16 and 17 onto the barrel 11, or bar 12. In order to insure tight contact of the flat extension 36 of the frame 29 against the undersurface of the bracket 45 a spring washer 88 is provided and disposed between the extension 36 and the washer 43. The provision of the spring washer 88 insures somewhat smoother action of the device as it compensates for wear between the adjacent parts at this point.

The leaf spring 90 shown in Figure 11 is somewhat different in form than the spring 31 previously described. The leaf spring 90 has one of its ends 91 bent over the end of the flange forming a part of the channel 27 and extend along the outer surface thereof to a hole 92 where it is bent inwardly to secure the spring 90 thereto. Its other portion 93 is bowed outwardly away from the channel 27 over the frame 29 and extended along the inner surface of the channel a substantial amount to hold a target 10 in the frame 29. As the target 10 is thrown from the frame 29 it compresses the bowed out portion 93 of the spring 90 which thereby exerts a pressure against the target rim engaged thereby insuring a smooth and even discharge of the target from the frame. Due to the light pressure exerted by the spring portion 93, the target 10 has a light friction imposed thereon as it leaves the frame whereby it is given a spinning motion which greatly assists its smooth and even flight through the air.

Briefly the operation of the mechanism of this invention is as follows: The first operation is

5 to secure the mechanism to either a gun barrel 11, or bar 12 adapted to be held by the handle 13, or to be supported upon a rod 14 adjacent to the user, by means of the clamp 16, 17. A target 10 is then placed upon the frame 29 and slid rearwardly to engage the flange 35 whereupon the spring end 39 will snap in the forward path thereof to releasably hold it in place. The frame 29 is then swung backwardly upon its pivot at the screw 44 into the position shown in dotted lines in Figure 2. The catch member 56 at its notch 57 will then be engaged by the sear-like depending end 58 of the trigger member 59 thus placing the mechanism in position to throw the target 10 into the air. The catch 56, and with it the frame 29, is then released by pressure upon the finger piece 72 to free the catch 56 from the member 58, whereupon the frame 29 will be rapidly and forcefully swung forwardly by the spring 53 and the target 10 thrown therefrom by centrifugal force. As the target 10 is so acted upon, it presses the spring end 39 outwardly to release itself therefrom.

25 Preferably the clamp 16, 17 is from two to six inches long, thereby being approximately from three to eight times longer than its diameter, to insure that it will cover sufficient area to obviate any danger of distorting a thin walled shotgun barrel 11, or of wobbling upon a bar 12 when it is actuated, its action, due to the relatively heavy spring 53, tending to loosen the mechanism from, or twist it about, its supporting member, the barrel 11, or bar 12. The provision of a target throwing mechanism which is adapted to be 30 detachably secured either to a barrel 11, or to a bar 12, permits its disposition in the most convenient location in respect to the user and whereby it may be actuated by him personally and without assistance from another, either when he is standing, kneeling, or lying prone, for target practice. Having all the operable parts attached to a common supporting member which forms one member, 17, of the means to clamp the mechanism to a barrel 11, or bar 12, greatly increases the convenience and efficiency of a mechanism of this nature and makes it one which is relatively simple in structure and inexpensive to manufacture. If desired the bar 12, when supported upon a rod 14, may be pivoted thereto as at 73 whereby the mechanism may be tilted at any angle.

55 While there has been shown and described herein one form of an improved target throwing mechanism, it is to be understood that the invention may be embodied in other forms without departing from the spirit and essential attributes thereof. It is therefore desired that the present embodiments be considered in all respects as illustrative and not restrictive, and it will be further understood that each and every novel feature and combination thereof, present in, or possessed by, the mechanism herein disclosed, forms a part of the invention included in this application.

60 What is claimed as new and for which it is desired to secure Letters Patent, is:

65 1. In a target throwing mechanism, a target holding frame, means to actuate said frame to throw a target therefrom, clamp means including separate upper and lower clamp members adapted when drawn together to embrace a supporting member to detachably secure the mechanism thereto, and common means to draw said clamp members together about the supporting

member and to secure said frame to the lower one of said clamp members.

2. In a target throwing mechanism, a target holding frame, means to actuate said frame to throw a target therefrom, clamp means including separate upper and lower clamp members adapted when drawn together to embrace a supporting member to detachably secure the mechanism thereto, common means to draw said clamp members together about the supporting member and to secure said frame to the lower one of said clamp members, and other means to draw said clamp members together and to secure the actuating means to the lower one of said clamp members.

3. In a target throwing mechanism, a target holding frame, means to actuate said frame to throw a target therefrom, and clamp means including separate upper and lower clamp members adapted, when drawn together, to embrace a supporting member to detachably secure the entire mechanism thereto, said frame and its actuating means being secured to one of said clamp members.

4. In a target throwing mechanism, a target holding frame, means to actuate said frame to throw a target therefrom, including means to pivotally support said frame, spring means extending rearwardly from said pivoting means to urge the frame forwardly to throw a target therefrom, a finger operated trigger member extending to the rear of said spring means, cooperating catch means between said frame and said trigger member, a releasable clamp having a lower member to which said frame pivoting means, said spring means, and said trigger member are secured, said lower clamp member being elongated from closely adjacent the rear end of said trigger member to beyond said pivoting means and adapted to partially surround and engage a supporting member over a considerable area of its peripheral surface, and means to detachably secure said lower clamp member to the supporting member.

5. In a target throwing mechanism, a target holding frame, means to actuate said frame to throw a target therefrom, including means to pivotally support said frame, spring means extending rearwardly from said pivoting means to urge the frame forwardly to throw a target therefrom, a finger operated trigger member extending to the rear of said spring means, cooperating catch means between said frame and said trigger member, a releasable clamp having a lower member to which said frame pivoting means, said spring means, and said trigger member are secured, said lower clamp member being elongated from closely adjacent the rear end of said trigger member to beyond said pivoting means, said clamp also including an upper member, and means to draw said clamp members together to embrace a supporting member therebetween, whereby said lower clamp member extending lengthwise along and over a considerable area of the peripheral surface of supporting member will protect the supporting member against strain and distortion imposed by actuation of said mechanism.

6. In a target throwing mechanism, a target holding frame, means to actuate said frame to throw a target therefrom, including means to pivotally support said frame, spring means extending rearwardly from said pivoting means to urge the frame forwardly to throw a target therefrom, a finger operated trigger member ex-

tending to the rear of said spring means, cooperating catch means between said frame and said trigger member, a releasable clamp elongated from closely adjacent the rear end of said trigger member to closely adjacent said pivoting means and including separate upper and lower clamp members adapted to embrace and grip a supporting member disposed therebetween over a considerable lengthwise area of its peripheral surface, and common means to draw said clamp member together to clamp the supporting member therebetween and to secure said frame pivoting means to the lower one of said clamp members.

15 7. In a target throwing mechanism, a target holding frame, means to actuate said frame to throw a target therefrom, including means to pivotally support said frame, spring means extending rearwardly from said pivoting means to urge the frame forwardly to throw a target therefrom, a finger operated trigger member extending to the rear of said spring means, cooperating catch means between said frame and said trigger member, a releasable clamp, elongated from closely adjacent the rear end of said trigger member to closely adjacent said pivoting means and including separate upper and lower clamp members adapted to embrace and grip a supporting member disposed therebetween over a considerable lengthwise area of its peripheral surface, common means to draw said clamp members together to clamp the supporting member therebetween and to secure said frame pivoting means to the lower one of said clamp members, and means to secure said spring means to the lower one of said clamp members.

8. In a target throwing mechanism, a swingable target holding frame, means to actuate said frame to throw a target therefrom, pivoting means for said frame, releasable trigger means 45 to hold said frame in target throwing position, a clamp comprising upper and lower members adapted to receive a holding member therebetween, means to draw said upper and lower members together to clamp a holding member disposed therebetween, said frame pivoting means, said trigger means, and said frame actuating means being secured to one of said clamp members to be supported thereby closely adjacent to the holding member.

55 9. In a target throwing mechanism, upper and lower clamp members adapted to partially surround the upper and lower portions respectively of an elongated supporting part, said lower member being elongated lengthwise to extend along the part to engage a considerable surface area thereof, means to draw said upper and lower clamp members together to clamp the supporting part therebetween, a target receiving frame pivoted to an end of one of said members, spring means reacting between said frame and the other end of the same clamp member to bias said frame forwardly of its pivot, a catch on said frame, and a trigger member, adapted to engage said catch to hold said frame rearwardly of its pivot against the action of said spring, secured to the same clamp member for sliding movement relatively thereto to release the catch therefrom.

10. In a target throwing mechanism, upper and lower clamp members adapted to partially surround the upper and lower portions respectively

of an elongated supporting part, means to draw said clamp members together to clamp the supporting part therebetween, a target receiving frame, means to pivot said frame to one end of one of the clamp members, spring means reacting between said frame adjacent its pivot and the other end of the same clamp member to bias said frame forwardly of its pivot, a catch on said frame, and a trigger member secured to the same clamp member to engage said catch to hold said frame against the action of said spring, said frame, said spring means and said trigger member being disposed closely adjacent to said supporting part when said clamp members are clamped thereabout.

11. In combination, a gun barrel, a target throwing mechanism, means comprising upper and lower clamp members each adapted to partially surround said gun barrel, means to draw said clamp members together to clamp said gun barrel therebetween, said target throwing mechanism being in its entirety secured to and supported by the lower clamp member to be disposed in an underslung position in respect to said barrel and closely adjacent to the underside thereof when the same is clamped between the said clamp members.

12. In combination, a gun barrel, a target throwing mechanism, means comprising upper and lower clamp members each adapted to partially surround said gun barrel, means to draw said clamp members together to clamp said gun barrel therebetween, said target throwing mechanism including a swingable target holding frame, a trigger, and spring means adapted to act on said frame to swing it to throw a target therefrom, means on said lower clamp member to which said frame is pivoted, means on said lower clamp member to support said trigger, and means on said lower clamp member to which said spring means is secured.

13. In combination, a gun barrel, a target throwing mechanism, means comprising upper and lower clamp members each adapted to partially surround said gun barrel, means to draw said clamp members together to clamp said gun barrel therebetween, said target throwing mechanism including a swingable target holding frame, a trigger, and spring means adapted to act on said frame to swing it to throw a target therefrom, means to pivotally secure said frame to said lower clamp member, means to secure said trigger to said lower clamp member, and means to secure said spring means to said lower clamp member.

14. In combination, a gun barrel, a target throwing mechanism, means comprising upper and lower clamp members each adapted to partially surround said gun barrel, means to draw said clamp members together to clamp said gun barrel therebetween, said target throwing

5 mechanism including a swingable target holding frame, a trigger, and spring means adapted to act on said frame to swing it to throw a target therefrom, means to pivotally secure said frame to said lower clamp member, and means to secure said spring means to said lower clamp member, one of the means to draw said clamp members together being arranged to secure said trigger to said lower clamp member.

10 15. In combination, a gun barrel, a target throwing mechanism, means comprising upper and lower clamp members each adapted to partially surround said gun barrel, means to draw said clamp members together to clamp said

15 gun barrel therebetween, said target throwing mechanism being in its entirety secured to and supported by the lower clamp member to be disposed in an underslung position in respect to said barrel and closely adjacent to the underside thereof when the same is clamped between the said clamp members, said target throwing

20 mechanism including a pivoted frame for securing and supporting a disc-like target, spring means to rapidly swing said frame to throw a target therefrom, said frame having side flanges between which the base of said target may slide, said side flanges converging toward each other toward the pivot point of said frame, resilient means to engage a disc-like target and releasably

25 hold it on said frame between the side flanges at the converging portions thereof, catch means on said frame, a trigger to engage said catch means to hold said frame against the action of said spring means to swing it, means to pivotally secure said frame to said lower clamp member, means to secure said trigger to said lower clamp member, and means to secure said spring means to said lower clamp member.

30 35 40 16. In combination, a supporting bar, a target throwing mechanism including an actuating trigger, means to secure said mechanism to said bar including upper and lower clamp members and means to draw said clamp members together to clamp the bar therebetween, said target throwing mechanism being in its entirety secured to and supported by one of said clamp members to be disposed spaced from and closely adjacent to the supporting bar when the same is clamped between the clamp members.

45 50 55 17. A target throwing mechanism comprising a target receiving frame, means to actuate said frame to throw a target therefrom, a trigger to release said frame actuating means, and clamp means including separate upper and lower clamp members adapted, when drawn together, to detachably secure the entire target throwing mechanism to a supporting bar clamped between said clamp members, said frame, its actuating means, and said trigger being secured to one of said clamp members.

HAROLD F. MOSSBERG.
